SCENERY PAPER

Conrad B. Maurer, Philadelphia, Pa., assignor to Maurer Paint Company, Philadelphia, Pa., a copartnership consisting of Conrad B. Maurer and Howard P. Maurer

Application May 2, 1940, Serial No. 333,050

6 Claims. (Cl. 41—34)

This invention relates to new and useful improvements in scenery papers and more particularly to such papers for forming miniature mountain, tunnel and like scenery.

More specifically the invention relates to scenery-forming paper of the character described which is capable of being manufactured in roll form and which is flexible or pliable to permit shaping by hand to produce miniature mountains, tunnels and the like.

With the foregoing in mind, the principal object of the present invention is to provide a scenery paper of the type described having secured on the surface thereof relatively small portions of a material which can be manipulated and formed by the user into suitable shapes representative of trees, bushes, shrubs and the like.

Another object of the invention is to provide a scenery paper of the character set forth which is fire-proof and so coated and colored that when said paper is rumpled, creased or otherwise manipulated by hand realistic scenes may be produced symbolic of snow covered mountains and having portions respectively symbolic of grass, mineral deposits, rocks, etc.

A further object of the invention is to provide a scenery paper of the stated character which may be manufactured at small cost and which possesses the further advantage of being able to be smoothed out after use, formed into a roll and reused as occasion may arise.

These and other objects of the invention and the various features and details thereof are hereinafter fully set forth and described and shown in the accompanying drawing, in which:

Figure 1 is a view illustrating the scenery paper of the present invention in miniature mountain formation.

Figure 2 is a view of a sheet of the scenery paper illustrating the treated face or surface thereof.

Figure 3 is a fragmentary view in perspective showing the manner in which the portions of material secured to the surface of the paper may be manually formed to represent trees, bushes, shrubs and the like; and

Figure 4 is a view in perspective showing a modification in the manner of securing the portions of said material to the scenery paper.

Referring now more particularly to the drawing, according to the present invention the scenery paper is manufactured by coating or printing a surface of suitable paper stock with coloring matter to produce areas thereon sym-

bolic of snow, grass, minerals, rocks and the like.

The paper stock employed is preferably a good grade of tough pliable wrapping paper and the coloring materials with which the surface of the paper is coated are preferably dextrene base water color paints. The paint is applied to the surface of the sheet in patches or areas of different color representative of the natural surface colorings of mountainous regions as indicated, for example, by the variously lined portions in Figure 2 of the drawing.

Water color paints such as those above mentioned have certain moisture-absorbing properties which operate to preserve the pliability and flexibility of the paper when coated thereby and such paints are further characterized by their quick drying properties which permit of manufacture of the scenery paper by continuous methods wherein the paper stock may be drawn or fed from a supply roll thereof, printed or painted and then re-rolled at the end of the machine ready for immediate shipment and sale.

Ammonium sulphate may be employed to render the scenery paper fire-proof and as this compound is soluble in water it may be initially added to the dextrene base water color paints and applied therewith to the surface of the paper stock, thus eliminating the necessity for an independent fire-proofing step as heretofore practiced in the manufacture of scenery and like papers.

A particular feature of the present invention resides in the application to the coated or painted surface of the scenery paper of small tufts or portions of material which can be manually formed into shapes representative of trees, shrubbery, bushes and the like. To this end, there is applied to the treated surface of the sheet, at random intervals thereon, relatively small portions or wads of metallic wool or the like. These are secured upon the treated surface of the sheet in relative flattened or compressed form by means of a suitable adhesive such as, for example, a latex or like adhesive composition which, while quick drying and adhering, does not become hard or brittle and thus prevent or hinder flexing and shaping of the scenery paper. These wool tufts may be, and preferably are, applied to the paper in the course of manufacture thereof after the same has been printed or painted as above described. These tufts or wads of metallic wool are indicated by reference character A, and the inter-

lacing fibres or filaments thereof are colored green to simulate or represent foliage.

The nature and interlacing filament or fibre structure of these tufts or wads of metallic wool are such that they may be manually manipulated and shaped, in the manner indicated in Figure 3, into formations representative of trees, shrubbery, bushes and the like, as desired. Various other types of wool such as glass, mineral, slag and the like can be used for this purpose but I prefer to use metallic and particularly steel wool therefor because it is comparatively dense and also because the interlacing and entanglement of the fibres or filaments thereof are such that they will not pull apart during manipulation and shaping as readily as will the other types of wool. Furthermore, metallic wool will better retain the shape to which formed due to its greater body and density, yet, when it is desired to put the scenery paper away for future use the wads of metallic wool can be flattened out and rolled up with the said paper. The form and shape of the metallic wool portions may be changed and varied as often as desired without destroying the density thereof or pulling it apart.

In Figure 4 of the drawing, I show an alternate manner in which wool may be applied to the scenery paper to represent trees, bushes and the like. In this particular arrangement suitably shaped tabs or flaps B are cut from the painted or printed paper and tufts or wads of wool C are secured to both sides of the tab as indicated. In use, this tab or flap B together with the wool C secured thereto is merely folded or bent into a vertical upstanding position as shown in said Figure 4 and in this form of the invention, the wool does not require manipulation and shaping to the full extent necessary in the arrangement shown in Figure 3 since the tab or flap B cut in the sheet as well as the wool C secured to both faces thereof are usually of a predetermined configuration in order that bent upright there is represented, for example, as shown in Figure 4, a generally triangular or conical shape symbolic of an evergreen tree.

The scenery paper thus produced is possessed of sufficient body so that it is substantially self-supporting when crumpled to the desired configuration such as a miniature mountain, hillside, tunnel or the like, and no braces, frame-work or other supporting structure need be employed in conjunction therewith. The scenic effect produced by the paper and the wool trees, shrubbery and the like thereof is realistic and because the paper with the wool thereon may be purchased in flat sheet or roll form as desired, at nominal cost, and can be flattened out and re-rolled after use, the said scenery paper is most desirable for holiday and other decoration.

From the foregoing it will be seen that the present invention provides a scenery paper embodying novel features of construction and arrangement which is very attractive and capable of being manufactured at relatively low cost, and while certain ramifications of the invention have been illustrated and described, it is to be understood that said invention is not limited to such disclosure but that changes and modifications may be made and incorporated therein within the scope of the annexed claims.

I claim:

1. Scenery-forming paper of the character described comprising a sheet of relatively tough pliable paper having its surface coated to symbolize snow, grass, rocks and the like, and a plurality of tufts of metallic wool secured at random intervals to said sheet and arranged for manual manipulation into positions symbolic of trees, shrubbery, bushes and the like.
- 5 2. Scenery-forming paper of the character described comprising a sheet of relatively tough pliable paper having its surface coated to symbolize snow, grass, rocks and the like, and a plurality of tufts of metallic wool secured at random intervals to said sheet and arranged for manual manipulation into positions symbolic of trees, shrubbery, bushes and the like, said paper being sufficiently pliable to permit crumpling thereof without cracking and stiff enough to retain a fashioned position.
- 10 3. Scenery-forming paper of the character described comprising a sheet of relatively tough pliable paper having its surface coated to symbolize snow, grass, rocks and the like, and a plurality of tufts of metallic wool adhesively secured at random intervals upon the coated surface of said sheet and arranged for manual manipulation and shaping into formations symbolic of trees, shrubbery, bushes and the like.
- 15 25 4. Scenery-forming paper of the character described comprising a sheet of relatively tough pliable paper having its surface coated to symbolize snow, grass, rocks and the like, and a plurality of tufts of metallic wool adhesively secured at random intervals upon the coated surface of said sheet and arranged for manual manipulation and shaping into formations symbolic of trees, shrubbery, bushes and the like, said paper being sufficiently pliable to permit crumpling thereof without cracking and stiff enough to retain a fashioned position.
- 20 30 45 5. Scenery-forming paper of the character described comprising a sheet of relatively tough pliable paper having its surface coated to symbolize snow, grass, rocks and the like, tabs cut at random intervals in said sheet and arranged to be folded into positions perpendicular to the surface thereof, and wads of wool-like material secured to opposite sides of said tabs and arranged when the latter are disposed perpendicular to the coated surface of the sheet to symbolize trees, shrubbery, bushes and the like upon said coated surface.
- 35 6. Scenery-forming paper of the character described comprising a sheet of relatively tough pliable paper having its surface coated to symbolize snow, grass, rocks and the like, tabs cut at random intervals in said sheet and arranged to be folded into positions perpendicular to the surface thereof, and wads of wool-like material secured to opposite sides of said tabs and arranged when the latter are disposed perpendicular to the coated surface of the sheet to symbolize trees, shrubbery, bushes and the like upon said coated surface, said paper being sufficiently pliable to permit crumpling thereof without cracking and stiff enough to retain a fashioned position.
